UNITED STATES PATENT OFFICE.

JOHN JAY ANTHONY, OF MOSCOW, IDAHO.

SHOP TOOL.

Application filed August 30, 1920. Serial No. 407,035.

To all whom it may concern:

Be it known that I, JOHN JAY ANTHONY, a citizen of the United States, and residing at Moscow, in the county of Latah and State 5 of Idaho, have invented a new and useful Improvement in Shop Tools, of which the following is a complete specification.

My invention pertains to that class of tools known as vises, particularly to that variety 10 called rapid action, and wherein a slidable jaw provided with a rotatable, handled drawbar bearing a cam-operated ratchet-nut has sliding engagement with a stationary jaw provided with a co-ordinating 15 ratchet-bar.

My object is to provide an extremely simple, light, quick acting and efficient vise, and one that will not clog with chips or other trash, nor readily get out of order, and one 20 that may be cheaply made of fabricated metal stampings and forgings, and marketed at a minimum of cost to the purchaser.

How I attain my object will be readily understood from a perusal of the following 25 description, and by study of the accompanying drawings, which are to form a part of this specification, and in which like reference numerals indicate corresponding parts in the several views.

30 In these drawings Fig. 1 represents my invention as in place on an ordinary bench-plank, and in neutral position or out of engagement, the jaws being partially opened. Fig. 2 is a side view when in engagement, and Fig. 3 a longitudinal, vertical section through the center. Fig. 4 is a front elevation, and Fig. 5 the same when handle is removed. Fig. 6 is a rear view when tail-spring is removed, and Fig. 7 a vertical 35 transverse section through the center. Fig. 8 is a side view of the drawbar and its accessories, and showing a modified form of handle. Fig. 9 is a side view of a modified form in which the drawbar and handle are 40 in one piece, and the gripping action secured through a worm on the drawbar and within the ratchet nut, instead of through cam on handle, and wherein, also, the drawbar housing is of a modified form of cross-section, 45 and has sliding engagement with a pair of parallel ways secured to the stationary jaw, instead of telescoping within a housing so secured; whilst Fig. 10 is a similar view of 50 such modified form of drawbar and accessories, a portion at the rear being cut away therethrough so as to show a longitudinal

section. Fig. 11 is a view from above of the stationary jaw, showing it as tapered at the rear for the sake of lightness. Fig. 12 is a vertical cross-section through the modified 60 form shown in Fig. 9; Fig. 13, a similar section through another modified form, in which the drawbar housing is of triangular cross-section and slidable between a pair of parallel ways of modified form secured to 65 the stationary jaw; whilst Fig. 14 is a similar section through another modified form, and wherein the drawbar, instead of being enclosed in a tubular housing of the slidable jaw, is carried between a pair of parallel 70 bars or tubes in sliding engagement within a corresponding parallel pair of tubes or 75 housings secured to the stationary jaw, a similar housing being employed between them for carrying the ratchet nut on the drawbar and allocating it. Fig. 15 is a plan view of a modification of the ratchet-bar, showing it provided with perforated ears for riveting to the stationary jaw, or for securing by screws to the bench-plank. Fig. 80 16 is an end view of the engagement cam, whilst Fig. 17 and Fig. 18 represent modified forms of tail-springs.

In greater detail, my invention comprises 85 two main members, a stationary member (hereinbefore and hereinafter styled stationary jaw) and a slidable member (hereinbefore and hereinafter styled slidable jaw), in telescopic or sliding engagement, the one 90 with the other. The stationary jaw comprises a flat body portion 1, perforated for fastening to a bench-plank by screws or bolts; an upright portion 2, the jaw proper, formed on the front end of the body portion; a tubular runway or housing 3 depending from the body portion; and a ratchet 95 member 4 (hereinbefore and hereinafter styled ratchet-bar) within the housing and secured to the body portion or to the bench 100 plank to which the body portion is secured.

The body portion 1 and the upright portion 2 are preferably formed of one sheet of fabricated metal, the depending housing 3 being formed of another sheet and secured to the body portion by riveting or welding, or it may be secured to the bench plank by bolts or screws, or a combination of methods may be used. Or the three parts may be fabricated in one piece from the same sheet, or cast integral. The ratchet-bar is parallel 105 with the body portion and the housing, which are to be perpendicular to the upright 110

portion. It may be of various forms, but its under surface shall be transversely serrated, either by milling or forging, so as to form downwardly projecting parallel teeth 5, 5 preferably slightly under-cut for purposes of readier engagement with the ratchet-nut, and with edges practically sharp for the same purpose.

The slidable jaw comprises a tubular body 10 portion 6; an upright portion 7, the jaw proper, formed on the front end thereof and perpendicular thereto; a cam 8 on the front face of the jaw at the lower part thereof, a hole 9 through the jaw and communicating with the chamber in the body portion. The body portion is preferably fabricated from drawn tubing, or from metal stampings, and the jaw cast thereon; but the two may be cast in one piece. It may be 20 of various forms of cross-section, preferably that shown in Fig. 7, though I am using that shown in Fig. 12, and may be either closed or partially open on the under side. The upper side is of curved contour or 25 sloping to either side from a longitudinally central line, so that chips or shavings may not readily lodge thereon and interfere with the action by clogging. Instead of the tubular body portion, however, may be substituted a pair of parallel bars or tubes, as 30 shown in Fig. 14, the drawbar being exposed and carried between them, in which case the ratchet nut will be carried in the stationary housing and a pair of similar 35 housings be provided, one on either side thereof, for engaging with the substituted bars or tubes.

Within the tubular body portion 6 and extending longitudinally therethrough and 40 through the hole 9 is a rotatable drawbar 10 provided at its front end with a handle 11 having a cam 12 on the inner face thereof for engaging with the corresponding cam 8, and at its rear end bearing loosely mounted 45 thereon a ratchet nut 13 having its upper face serrated to correspond and engage with the under face of the ratchet-bar of the stationary jaw, and an engagement cam 14 securely fastened at the rear of the ratchet-nut. The serrations 15 of the ratchet-nut 50 are in all respects similar to those of the ratchet-bar.

The pitch of the cams must be very coarse, preferably not less than three or four 55 times that of the teeth of the ratchet members, in order that early engagement may be secured and the work made fast before the accomplishment of a full turn of the handle and drawbar.

I prefer to make the cams of spiral contour, as shown in Fig. 5. The handle may 60 be of any suitable form and construction, and secured to the drawbar in any approved manner; or it may be forged or cast integral therewith, as shown in Fig. 9 and

Fig. 10, or it may be slidable in a hole through the head thereof, as shown in Fig. 8.

The upper part of the rear end of the tubular body (drawbar housing) 6 is cut 70 away for a short distance, as shown at 16 in Fig. 9 and Fig. 3, or has a slot cut therein for the upward egress of the ratchet nut, and to permit a certain amount of end play for the same when the grip is tightened, the amount of such end play necessary being the takeup or draw of the spiral cams; but it may not be much greater, lest it annoy the operator. As small a portion as practicable is cut away, the remainder being turned up to a vertical position at either side of the ratchet nut, as shown at 18 in Fig. 2 and Fig. 6, so as to form a comparatively close fitting housing therefor, to keep it from tipping when the drawbar is rotated, and so prevent it from jamming with the ratchet bar above.

The engagement cam 14 is a circular disc with a portion of its lower edge cut away to form a flattened portion which, when the vise is in neutral position, rests on the floor of the drawbar housing, or on a rearwardly extending portion thereof forming a cam rest 19, which cam rest may be integral with said housing floor or a separate 95 part secured thereto for the purpose.

For the sake of smoother action in engagement, and to secure an elastic or cushioning grip, a spring washer 20 is mounted on the drawbar between the ratchet-nut and engagement cam, which arrangement provides for easier engagement of the nut when in certain position, and causes that the jaws shall work loose from the work less easily.

Also, to keep the ratchet-nut back against 105 said washer and prevent it from being suddenly drawn forward against the drawbar housing, to the annoyance of the operator, an encircling spiral spring 21 is mounted on the drawbar in front of said nut, and in 110 contact therewith, and held in place by a collar 22 bearing against a suitable stop 25 secured to the drawbar housing, preferably to the floor thereof, as shown in Fig. 3.

The collar 22 may, however, be omitted, as also the stop 25, and a longer spring be used bearing against the slidable jaw, the stop and collar serving but to economize in the use of spring.

Also, to aid in releasing the engagement, 120 and to prevent the ratchet-nut from jumping up into engagement when the handle is precipitately drawn forward, and so interfering with the opening of the vise, a tail spring 23 is provided connecting the rear 125 end of the drawbar with the rear end of the cam rest. But such tail spring is not essential, since with a little practice, the operator will have no difficulty in the matter of such interference.

In the matter of securing the engagement cam to the drawbar, I have preferred to thread them and screw them together with the cam in its proper position on the bar, and then to lock the cam securely by means of a jam-nut 24 screwed onto the drawbar to the rear of the cam, as shown in detail in Fig. 3. But I would be permitted to use any other suitable method.

10 If the modified form shown in Fig. 14 be used, as will be sometimes desirable, the central housing which supports the ratchet-nut, may be discarded, and the nut supported and held in proper position by a suitable 15 cross-piece tieing together the rear ends of the parallel bars of the slidable jaw, which would necessitate longer bars than would otherwise need be used, and longer than the drawbar or its housing.

20 The ratchet-bar 4 I prefer to make with rectangular projections 25 on its upper side for engagement with the stationary body portion 1, through perforations made therein for the purpose, as shown in Fig. 11, where 25 holes are shown, also, in the projections, and through which screws or bolts are passed to secure the piece to the bench-plank, the holes being counter-sunk on the under side for the screw-heads. It may sometimes be better to 30 employ the form of ratchet-bar shown in Fig. 15, where perforated ears are formed on either side, and through which it is secured to the bench-plank in similar manner, or to the stationary body by means of rivets. It 35 may, however, have no projections and be welded to the body, or a combination of methods may be used.

In operation the vise is manipulated as follows: The handle is turned to upright 40 position, whereby the ratchet-nut drops out of engagement by gravity, the tail-spring aiding. The handle is then given a pull forward perpendicularly to the faces of the jaws, thus causing them to separate. The 45 work is then inserted between them and the handle pushed back in the opposite direction until the slidable jaw presses against it, whereupon the handle is given a quick turn in the proper direction (in this instance to the right) causing the engagement cam to 50 lift the ratchet-nut into engagement with the ratchet-bar, and at the same time bringing the cams of the jaw and handle into action, forcing the jaw tightly against the work. To release the work the handle is 55 given a partial turn in the opposite direction.

Having thus fully described my invention and shown its manner of operation, I claim 60 the following as new and patentable, and pray that Letters Patent be granted me thereon:

1. In a bench-vise and in combination, a flat horizontal body portion, perforated for 65 securing to a bench-top; an upright portion

or jaw formed on the front end thereof and perpendicular thereto; a hollow portion on the under side of said body portion and parallel therewith, and perpendicular to said upright portion, and forming a tubular 70 guideway open at both ends; a ratchet member within said hollow portion and extending longitudinally therethrough and secured to the body portion parallel therewith; parallel serrations or teeth in said ratchet member transversely across the under surface thereof, and slightly undercut; a movable tubular portion or casing in telescopic engagement within said hollow portion and open at the rear end; an upright portion or jaw formed on the front end of said movable tubular portion perpendicular thereto and parallel with the aforesaid upright portion on said body portion, and having a spiral faced projection on its front face at the lower central part thereof, and there being a hole therethrough in communication with the chamber within said movable tubular portion; a rotatable drawbar within said chamber and extending 80 longitudinally therethrough and through said hole; an operating handle on the front end of said drawbar for the rotation thereof; a spiral faced projection on the inner face of the hub of said handle and registering with the aforesaid like spiral projection on said last-named jaw, and forming a cam for co-ordinate action therewith; a ratchet engagement nut loosely mounted on said drawbar near the rear end thereof for 85 intermittent engagement with the aforesaid ratchet member; parallel serrations or teeth transversely across the upper face of said nut for inter-locking engagement with the like serrations of said ratchet member; a cam on said drawbar to the rear of said engagement nut for the lifting thereof into engagement, and a lock-nut for securing the cam in place; a spring washer on said drawbar between said engagement nut and said cam; a spiral spring on said drawbar in front of, and adjoining said engagement nut, and means for holding said spring in contact with said nut; a suitable cam-rest or support for said cam; a tail-spring secured by its lower end to the rear end of the bottom of said movable tubular portion, and having its upper and free end bearing downwardly upon the rear end of the drawbar; all as shown and described, and for the purposes set forth.

2. In a bench-vise and in combination, a stationary member comprising a horizontal flat body portion, perforated for securing to a bench top, and having an upright portion or jaw formed on its front end perpendicular to the body portion, a tubular portion or casing on the under side of the body portion and parallel therewith, and depending therefrom, and perpendicular to the plane of the 125 130

- upright portion, and open at both ends, and containing a ratchet-bar having transverse serrations across its under surface and perforated projections or ears along its sides for securing to the body portion or to the bench to which the body portion is secured; and a movable member comprising a tubular body portion or casing having sliding engagement with the stationary member and telescoping within the depending tubular portion thereof, and open at the rear end, and provided at the front end with an upright portion or jaw parallel with the jaw of the stationary member, a spiral faced projection on the front face of said jaw at the lower central part thereof and centrally pierced by a hole communicating with the chamber within the tubular body portion, a rotatable draw-bar within said chamber and extending longitudinally therethrough and furnished at its front end with an operating handle having a spiral-faced projection on the inner face of its hub in registering contact with the like projection on the jaw and loosely mounting at its rear end an engagement nut having parallel serrations across its upper face, a cam of circular contour secured to said draw-bar to the rear of said nut and resting upon the rear end of the bottom of the tubular body, a flattened portion at bottom of said cam, for resting on the floor of said tubular body, and means for maintaining the several parts in place, as shown and described.
3. In a bench-vise, the combination of a stationary member comprising a flat body portion, a jaw formed on the front end thereof and perpendicular thereto, and a tubular casing parallel with said body portion, open at the ends and depending therefrom and secured thereto and containing a serrated ratchet bar; and a movable member in sliding engagement with said stationary member and comprising a tubular body portion or draw-bar housing telescoping within said tubular housing of the stationary member and open at its rear end and provided at its front end with an upright jaw having on its lower front face at the central part thereof, a sloping or wedge-shaped projection and there being a hole therethrough communicating with the chamber within said draw-bar housing, a rotatable draw-bar within said draw-bar housing and extending therethrough and through said hole, and furnished at its front end with a handle having a wedge-shaped or sloping projection on the inner face of its hub in registering contact with the similar projection of the jaw and at its rear end a loosely mounted serrated engagement nut, and a securely fastened cam to the rear of said nut, and a spring washer between said cam and said nut, for the purposes explained.
4. In combination in a vise, a stationary member comprising a horizontal body portion with a jaw formed thereon, a pair of parallel tracks or ways on the under side thereof and secured thereto, or integral therewith, and a serrated ratchet-bar between said ways; and a slidable member in engagement therewith between said ways and comprising a tubular body, open at the rear end and furnished at its front end with an upright jaw, a rotatable draw-bar within said tubular body, furnished at its front end with a handle and bearing at its rear end a serrated ratchet-nut and a cam to the rear of said nut for its operation, a sloping projection on the lower part of the front face of said jaw, and a similar projection on the contiguous face of said handle for co-ordinate action therewith.
5. In a vise and for use with a suitable stationary member thereof, a slidable member comprising a tubular body, open at the rear, a jaw on the front end of said tubular body, there being a hole through said jaw in communication with the interior of said tubular body, a rotatable draw-bar through said hole and said interior, a handle on the front end of said draw-bar, cam action between said handle and said jaw, a serrated ratchet-piece loosely mounted on said draw-bar near the rear end thereof, and a cam secured thereto at the rear of said ratchet-piece, an opening in the upper part or roof of said tubular body for the upward egress of said ratchet-piece, substantially as shown and described.
6. In a vise and for operation in the movable jaw or member thereof, a rotatable draw-bar through said jaw and having a handle on its front end, cam action between said handle and said jaw, a serrated ratchet member, loosely mounted on said draw-bar at its rear end, a cam secured to said draw-bar at the rear of said ratchet member, a spring washer between said cam and said ratchet member, and a spring between said ratchet member and said jaw.

JOHN JAY ANTHONY.
